UNITED STATES PATENT OFFICE.

GRAYSTON L. OHMAET, OF DETROIT, MICHIGAN.

DISHWASHING MACHINE.

Application filed November 7, 1921. Serial No. 513,288.

This invention relates to dish washing machines and has for its object a machine that embodies several new features and improvements.

5 The revolving spray type of washing machine is not broadly new. It is the object of the present invention to afford an improved machine of the revolving spray type which has upwardly-directed water jets, 10 laterally-directed water jets and downwardly-directed water jets. The arrangement of these jets is such that each is projected through a portion of the washing chamber that is not reached by the other 15 jets, that is to say, the jets are arranged so that in rotating through the washing chamber one jet following the preceding jet does not strike exactly the same spot but is intended to have an effective swing that does 20 not exactly coincide with the jets that have gone before in the cycle of rotation. In this way almost every unit of the washing chamber is subjected to a high velocity water jet so as to more effectively cleanse and wash 25 the dishes.

Another important improvement in this revolving spray washing machine is that no nozzles are used. Simple perforated spray arms are used at the bottom while a perforated spindle with rose heads serves to distribute the water through the upper dish racks. This is an important improvement over a revolving spray having nozzles carried on the spindle for it permits suitably 35 formed dish racks to be threaded easily over the upstanding spindle and the rose heads. This enables the washing chamber to be charged with the racks from the top, which is more convenient and eliminates the trouble of side closure which may result in 40 leakage.

Another important improvement is the arrangement for discharging the dirty water when the washing operation is finished. By 45 turning a valve the water instead of being pumped to the revolving spray is pumped out of the machine and may be discharged through a flexible hose to a sink or any other convenient point of discharge.

50 The water is strained by a special form of removable strainer which is accessible from the outside of the machine without opening any doors, slides, or reaching into the machine.

55 The revolving spray is coupled up with the pump connection by a detachable cou-

pling which permits the entire spray to be removed easily at any time for cleaning. These and other features will be better understood when a full description of the machine is given.

In the drawings,—

Fig. 1 is a perspective showing the outside of the machine and showing how the same may be moved up to a sink to discharge the dirty water after a washing.

Fig. 2 is a vertical cross section of the machine.

Fig. 3 is a section taken on the line 3—3 of Fig. 2, part of the bottom of the washing chamber being broken away.

Fig. 4 is a plan view of the upper dish rack showing the dishes in place.

Fig. 5 is a fragmentary section showing how the cover forms a tight joint with the side walls of the machine.

Fig. 6 is a cross section on the line 6—6 of Fig. 2.

Fig. 7 is a fragmentary vertical section of the strainer sump and the parts of the machine adjoining.

Fig. 8 is a section on the line 8—8 of Fig. 7.

Fig. 9 is a plan view of the lower dish rack.

Fig. 10 is a vertical section of the rotating spindle.

Fig. 11 is an enlarged section of the spindle at the bottom showing the coupling with the pump connection.

Fig. 12 is an enlarged vertical section of the lower rose head showing in detail the position of the jet orifices.

Fig. 13 is a diagrammatic or plan view of the revolving spray showing the arrangement of jet openings so as to cause each jet to reach a different territory in the washing chamber.

Fig. 14 is a cross section taken on the line 14—14 of Fig. 13.

Fig. 15 is a cross section taken on the line 15—15 of Fig. 13.

The operating parts are contained within a neatly constructed cabinet that is square in horizontal cross section, as appears in Fig. 1. Preferably the outside walls are sheet metal enameled in any suitable color. The corners are reinforced and ornamented by nickel plated strips *a*. A closure or lid is carried by strap hinges *c* which also carry the arms *b* which act as a stop for the lid when swung back. The cabinet may be

rolled over the floor on the casters *d* (Fig. 2). The cover is made of sheet metal, as is shown in Fig. 2, and on the under side near the outer edge it is grooved and corrugated *e* as at *e* to fit tightly over the rounded top of the side walls of the cabinet. This is clearly shown in Fig. 5. The upper part of the cabinet is provided with a water-tight dish washing chamber having the inclined floor *f*.

The lower part of the cabinet serves as a housing for the motor *M* and the centrifugal water pump *g*. This pump takes water from the pipe *h* which is connected with the strainer sump *i*. The strainer sump is simply a cylindrical sump set on an oblique axis and provided on its upper end with a metal seat *j* that is provided with an inner surface in the form of the frustum of a cone. An oblique passageway *k* in the side of the cabinet connects the strainer sump with the exterior. This permits a special form of strainer such as shown in Fig. 7 to be used and which may be removed from the exterior of the machine without in any way reaching into it. The strainer is a cylindrical screen *m* carried on a spider *n* which is connected by a stem *o* with an obliquely-set plate *p*. This plate is obliquely set to the axis of the strainer and stem but on the exterior of the machine is simply a flat plate, as shown in Fig. 1, provided with a center depression leaving a strap *q* by which the strainer may be grasped. This arrangement permits the strainer to be removed without opening the machine or removing the dish racks and at the same time avoids all unsightliness on the exterior of the machine. Furthermore, the mouth of the passage-way through which the strainer is removed is located high enough above the bottom of the floor of the washing chamber so as not to cause leakage. The top of the strainer is provided with a collar *r* adapted to fit into the ring *j* so as to make a fairly water-tight connection. This prevents any of the used water from running down on the outside of the strainer and escaping the straining operation.

Obviously the floor *f* of the washing chamber is sloped to drain down into the strainer. The water is taken through the pipe *h* into the pump *g*, is then forced up into a casting or fixture *s*, then through suitable pipe connections *t* up into the coupling head *u* (see Fig. 11). The coupling nut *v* screws onto this coupling head with an interposed graphite bearing washer *w*. This secures the revolving spray in place by reason of the flange *x* on the lower end of the revolving spray. This flange is carried on the pipe section *y* that screws into the pipe coupling *z* and at the upper end of the pipe coupling the vertical tube 1 is screwed, while the horizontal spray arms 2 and 3 are fixed

in the side of the coupling. The vertical spindle is made up of three tubes or pipe sections connected by two couplings or rose heads 6 and 5, upper and lower respectively.

These three tubes and the two couplings or rose heads form the vertical spindle of the revolving spray. The upper and lower tubes or sections are perforated to form jet openings 4' and 5'. The jet openings of a single tube are in vertical lines opposite each other but note that the openings are staggered on opposite sides of the tube. This means that each of the upper and lower vertical tubes will throw horizontal jets but they will strike at different heights as they rotate, no two jets striking at the same height. In Fig. 12 the arrangement of the jet openings in the rose heads is shown. Each of these rose heads throws two fan shaped sprays of water. The lower rose head 5 throws upwardly while the upper rose head 6 throws downwardly. This is shown in Fig. 10. Now referring to Fig. 12, it will be seen that this line or fan arrangement of jets is illustrated and that one line or fan arrangement is located diametrically opposite the other on the rose head. However, the individual jet openings on opposite sides of the rose head are staggered. Note the degrees at which they are set. The jet openings of the spray arms 2 and 3 are bored obliquely and oppositely directed on the two arms so as to rotate the spray upon the re-action principle (see Figs. 14 and 15).

Now referring to Fig. 13, which is a diagrammatic view, it will be seen that each line of jet openings is arranged so as to complement the other in an attempt to reach as even a distribution of water throughout the dish washing chamber as possible and to cause each jet to reach its own territory and not duplicate the territory reached by some other jet as the various jets revolve around in their cycle of operation. Note that the upwardly-projected jets of the horizontal arms 2 and 3 are in lines nearly opposite each other at 180 degree points, (the lines are slightly offset to rotate the spray). The plane of the jet holes in the upper rose head is 30 degrees removed at each side from the upward spray. The plane of holes in the lower rose head is 60 degrees removed from each upward spray and 90 degrees removed from each fan of water from the upper rose head. The plane of the jet holes in the upper and lower vertical tubes is 45 degrees removed from each of the fans of water from the upper and lower rose heads and 75 degrees removed from each upward spray. This means that none of the jets strikes exactly the same territory that the other jet does in its cycle of operation. Even the arrangement of the jet openings on the horizontal arms is staggered on opposite sides of the vertical spindle, that is,

each jet hole is a different distance removed from the center of the spray.

The top dish rack or basket is a wire basket in the form of a shallow cylinder with two rails 7 and 8. These extend only part way around the circle. The inner rail 8 is the lower and located upon an arc of smaller diameter, while the outer rail 7 is the higher and located on an arc of larger diameter. These two rails are very nicely calculated to hold up glasses and cups, as is shown in Fig. 2. The glasses may be rested with their open ends on the lower rail and their upper ends resting on the top of the higher rail 7 so as to tilt them in such position as to have their openings directly face the spray. In the same way the cups may be set on the outside of the higher rail 7 between the glasses or other vessels held between the two rails. This will bring these cups directly in the path of the horizontally-projected jets of the upper tube and the upwardly-projected jets from the lower rose head. The side of the upper basket which is not occupied by the rails 7 and 8 may be used to hold large plates, as shown in Fig. 4.

The lower basket or rack is intended to take flat ware and is provided with a plurality of circular rails of gradually increasing height from the center outward (see Fig. 2). These are arranged to take the flat ware which can be set edgewise and substantially vertically in between these concentric rails. At the center of the lower basket is a ring 9 that reaches the top of the basket and is held up by the uprights 10. This forms a center support for the upper basket and also the uprights 10 form a guard to prevent the plates from dropping over onto the revolving spray. Likewise the uprights 11 on the upper basket form a guard to prevent the dishes in the upper baskets falling on the revolving spindle. These rings on the upright form a convenient way of grasping the racks when charging or removing the baskets from the cabinet.

This arrangement of rose heads and baskets is important. By utilizing the jet openings in the rose heads, drilled on radii from the common center, a fan shaped spray of water is secured. This fan shaped spray of water secures substantially the results that would be obtained by having nozzles part way up on the spindle or at the top of the spindle for throwing the water upwardly or downwardly in vertical or oblique lines. With such nozzles the washing chamber could not very well be charged from the top. However, by employing these rose heads with jet openings drilled as I have described, the water distribution is as good and yet the rose head occupies so little space that the baskets may be threaded over the upstanding spindle and the rose heads.

The water is thrown with a high velocity

through the jet openings by reason of being forced into the spray by pressure from the pump *g*. This separate pump carried on the machine itself enables the machine to be operated with water in which a suitable washing compound has been introduced. The hot water with the washing compound is introduced into the top of the cabinet, the pump is started, and it pumps the water out of the bottom of the washing chamber and through the spray, in the meantime straining it. When the dishes have been sufficiently sprayed to remove all the soil, the machine is moved over to a sink, as shown in Fig. 1, and the hose 13 turned into the sink. The valve handle 14 is turned and this through the stem 15 throws the three-way valve 16, which turns the water from the pump into the discharge hose 13, and the pump quickly pumps out all the dirty water. The strainer may then be removed and cleaned and the same may be replaced and a quantity of rinsing water be thrown into the machine for rinsing the dishes. This completes the washing operation. The machine may be pumped dry again by simply turning the valve.

The water runs down through the strainer *m* into sump *i*, thence it is pumped up into the vertical spindle, the horizontal lines and the rose-heads from which it issues through the jet openings.

What I claim is:

1. In a dish washing machine, the combination of a cabinet provided with a washing chamber and a revolving spray having horizontal arms at the bottom provided with lines of upwardly-directed jet openings on the rear sides of said arms, and a vertical spindle provided with rose heads having jet openings, the said spindle also having jet openings in its sides, the jet openings in the spindle and in the rose heads arranged in vertical planes angularly with respect to the jet openings in the horizontal arms.

2. In a dish washing machine, the combination of a cabinet provided with a washing chamber and a revolving spray having horizontal arms with upwardly-directed lines of jet openings, and a rotating vertical spindle provided with rose heads having jet openings, said spindle being provided with jet openings at its sides, said jet openings of the spindle and the rose heads being arranged in lines angularly removed with respect to the lines of jet openings in the horizontal arms and with respect to the lines of jet openings in one another.

3. In a dish washing machine, a cabinet provided with a washing chamber and a rotating spray including a vertically rotating spindle having a pair of rose heads each drilled with a vertical line of diverging jet openings, one for projecting water in a fan-like arrangement upwardly and the other in

- a fan-like arrangement downwardly, the two lines of jet openings being angularly removed from each other.
4. In a dish washing machine, a cabinet provided with a washing chamber, a revolving spray rotated by one or more perforated horizontal arms at the bottom and having a central vertically rotating spindle provided with a pair of rose heads, the upper one of which throws a fan-like spray downwardly and the lower one of which throws a fan-like spray upwardly, and a pair of skeleton dish baskets that can be threaded over the spindle and rose heads and supported in the chamber above the horizontal arms.
5. In a dish washing machine, a cabinet having a washing chamber, a revolving spray rotated by one or more perforated horizontal arms at the bottom provided with vertically directed jet openings and provided with a central vertical rotating spindle having laterally-directed jet openings and a pair of rose heads on the spindle, the lower one of which throws a fan-like spray of water upwardly and the upper one of which throws a fan-like spray of water downwardly, and a pair of dish baskets which can be threaded over the spindle and the rose heads and supported in the chamber, both above the horizontal arms and one above the lower rosehead.
6. In a dish washing machine, a cabinet provided with a washing chamber, a spray therein, a pump located outside the washing
- chamber, connections between the washing chamber and the pump provided with a strainer sump and between the pump and the spray, and a cup-shaped strainer located in such sump and having a handle portion at the outside of the cabinet whereby the same may be removed without reaching into the cabinet.
7. In a dish washing machine, a cabinet provided with a washing chamber and having a strainer sump and a passage-way leading to the strainer sump, a spray within the chamber, a pump outside of the chamber for taking water out of the strainer sump and delivering the same to the spray, and a cup-like strainer carried on a long stem and fitting into the strainer sump and the stem passing through the oblique passage-way to the exterior of the cabinet.
8. In a dish-washing machine, a cabinet provided with a washing chamber and having an oblique strainer sump and an oblique passage-way leading from the side wall to the sump, a spray located in the washing chamber, a strainer located in the strainer sump provided with a long stem reaching through the oblique passage-way and provided with an oblique handle plate on the outer end of the stem which fits the side wall at the outside of the cabinet, and a pump for taking the water from the strainer sump and returning the same to the spray.

In testimony whereof I affix my signature.
GRAYSTON L. OHMART.
